UNITED STATES PATENT OFFICE.

DENNIS QUINLAN, OF BLUE PLAINS, DISTRICT OF COLUMBIA.

FASTENING DEVICE.

1,307,925.

Specification of Letters Patent. Patented June 24, 1919.

Application filed January 15, 1919. Serial No. 271,310.

To all whom it may concern:

Be it known that I, DENNIS QUINLAN, a citizen of the United States, residing at Blue Plains, in the District of Columbia, 5 have invented certain new and useful Improvements in Fastening Devices; and I do hereby declare the following to be a full, clear, and exact description of the invention, such as will enable others skilled in 10 the art to which it appertains to make and use the same.

This invention relates to fasteners, and more particularly to a cincture for the efficient and ready securing together of separate bodies and consists of a pair of complementary or reciprocal units capable of being interlocked with each other when mutually related to secure the binding together of the bodies.

20 It is an object of the present invention to provide an extremely simple, practical and inexpensive, substantial, durable and easily applied cincture or stitch-like fastening device. It is furthermore an object of 25 this invention to provide a cincture or thread-like stitch or fastening means capable of being applied with facility without the requirement of any special treatment or altering of the bodies to be secured 30 and without the necessity of the application of any special tools and which at the same time provides an entirely satisfactory and substantial fastener.

It is an important object of the present 35 invention to provide a cincture consisting of a pair of duplicate reversible interchangeable units which become reciprocal to form a complete cincture or stitch-like girdle to encompass or secure two or more 40 separate bodies in desired assembled relation, and a further object is to provide units which will be mutual in their co-action as units one upon the other to bring them to their respective places of rest without care- 45 ful measurements or peculiar tools, each of the units being so designed and constructed that they coöperate one with the other to secure the final assembled relation together.

With these and other objects in view, the 50 invention consists in the construction, the combination, and in details and arrangements of parts as more particularly described hereinafter relative to the embodiments of the invention described in the fol-

lowing specification and illustrated in the 55 accompanying drawings, in which:

Figure 1 is a perspective view of a fragment of two strap ends secured by the improved fastening, the strap ends being in section to illustrate the fastening in side 60 elevation;

Fig. 2 is an enlarged detail view of the cincture or fastening device partly broken away to illustrate clearly the interlocking of the units by riveting; 65

Fig. 3 is an enlarged detail sectional view of the overlapped strap ends in section and showing the units of the cincture in assembled relation and partly finished attachment; 70

Fig. 4 is a perspective view of one of the units;

Fig. 5 is a plan view of a blank of a modified form of the units; and

Fig. 6 is a perspective view of the completed unit. 75

While the present invention is capable of being constructed of units which may differ in various particulars and details, the general principle covering the construction of 80 the complete cincture or fastener involves a pair of unit members in the form of staples as shown in Fig. 4, these staples being made of any suitable material and of material of any suitable cross sectional form and other 85 outline, in the present instance each staple or unit 2 comprising a transverse or connecting bar 3 having a pair of parallel or substantially parallel legs 3-3 which preferably have their inner or opposed faces 90 plane, as indicated, the ends of the legs preferably being suitably pointed, as at 4, to facilitate the penetration by the legs of the material, such for instance the overlapped ends S. A feature of the present invention resides in perforating or having at one end of the transverse bar 3 of a unit an aperture 5, one side of which preferably lies close to the plane of the inside surface of one of the legs 3, so that after one of 100 the units has been driven through the bodies to be connected or securely fastened then a mutual or reciprocal staple or unit member going to complete the cincture may be positioned with its points substantially in contact 105 with complementary points and surfaces on the inserted unit 3 (see Fig. 3, dotted lines), whereupon the second unit 3 may be driven

with its points disposed oppositely to the previously driven unit, the legs of each of the units being mutually complementary to the other and therefore acting as units to direct the movement of the penetrating legs through the material to be secured together and finally so that the points of the legs which happen to be in a position inside or between the legs of the reciprocal staple are directed accurately and may be driven rapidly through the complementary aperture 5 provided therefor, in each of the transverse bars 3 of the staple units. After the units going to form the complete coupling or cincture have been driven completely home as shown in Fig. 3, those points of the staple legs which have penetrated the openings 5 and extend beyond the tops of the staples are designed to be clipped off as at *a*, Fig. 3, and then riveted close down while the point of the legs of the staples remaining outermost in the complete cincture may be clipped off close down to the surface of the connected bodies, as at *b*.

From the above, it will be seen that I have provided a cincture or girder or closed metallic stitch which will efficiently connect two separate bodies and which are designed to be mutual in their co-action as guides one on the other to facilitate the driving of the units to their final position of rest and connecting the bodies.

A slightly modified form of the body structure of the unit is illustrated in Figs. 5 and 6, in which case the bodies of the material of the transverse bar 3 are shown as laterally enlarged, as at 3' around the apertures 5 in order to preserve and maintain the maximum strength of the finished unit. Obviously the finished unit or staple has its legs folded down substantially perpendicular to the plane of the bar 3, the fold being made approximately on the line *f*—*f* perpendicular to the axis of the blank (see Fig. 5) so that at one side the opening

is substantially in the plane of the inside surface of the perpendicular leg.

What is claimed is:

1. A cincture unit consisting substantially, of a common wire staple with a straight cross-bar which is perforated on an axis parallel to the legs of the staple, the perforation having one side in the plane of the inside surface of one of the legs whereby said surface will act as a guide for a complementary unit of similar character when the units are being assembled. 55

2. A cincture unit consisting substantially, of a common flat wire staple with a straight cross-bar which is perforated on an axis parallel to the legs of the staple, the perforation having one side in the plane of the inside surface of one of the legs whereby said surface will act as a guide for a complementary unit of similar character when the units 60 are being assembled. 65

3. A cincture consisting of a pair of duplicate and interchangeable wire staples each having a straight cross bar which is perforated on an axis parallel to the legs of the staple, the perforation having one side in the plane of the inside surface of one of the legs so that said surface will act as a guide for a complementary unit of similar character when the units are being assembled. 70 75

4. A cincture consisting of a pair of duplicate and interchangeable wire staples each having a straight cross bar which is perforated on an axis parallel to the legs of the staple, the perforation having one side in the plane of the inside surface of one of the legs so that said surface will act as a guide for a complementary unit of similar character when the units are being assembled, the points of the legs which extend through the respective, reversely disposed units being clipped flush and riveted. 80 85

In testimony whereof I affix my signature.

DENNIS QUINLAN.
